UNITED STATES PATENT OFFICE.

WILLIAM S. HAMM, OF HUBBARD WOODS, ILLINOIS, ASSIGNOR TO THE ADAMS & WESTLAKE COMPANY, A CORPORATION OF ILLINOIS.

SIGNAL-LAMP.

1,288,570.

Specification of Letters Patent. Patented Dec. 24, 1918.

Application filed March 24, 1917. Serial No. 157,135.

To all whom it may concern:

Be it known that I, WILLIAM S. HAMM, a citizen of the United States, and resident of Hubbard Woods, county of Cook, and State of Illinois, have invented certain new and useful Improvements in Signal-Lamps, of which the following is a specification and which are illustrated in the accompanying drawings, forming a part thereof.

10 The invention relates to signal lamps of the top draft type, such as are shown in my Patents Nos. 651,782, of June 12, 1900, and 1,039,123, of September 24, 1912.

Lamps of this character have heretofore 15 been employed in situations where the air currents move in a horizontal, or approximately horizontal, direction. In recent railroad practice, however, a form of semaphore has come into use in which the lamp 20 is located back of a plate or shield having considerable vertical dimension. As a result air current moving toward the face of such shield break over the top thereof and descend vertically, or approximately so. Under 25 such conditions the lamp has a tendency to sweat, moisture generated by the flame being condensed upon the inner surface of the body and of the lenses. This phenomenon results from a disturbance or 30 reversal of the draft, the descending external air currents apparently inducing an outward flow of air through the ports provided in the top of the lamp for the admission of air to support combustion. When this action 35 occurs the vapors are not only permitted to spread to the walls of the lamp, but if an actual reversal of draft occurs they are drawn over to the lamp walls and lenses.

The object of this invention is to overcome 40 the difficulty referred to. The character of the invention is fully hereinafter pointed out, and is shown in the accompanying drawings, in which—

Figure 1 is a vertical central sectional 45 view of the lamp;

Fig. 2 is a transverse section on a reduced scale on the line 2—2 of Fig. 1; and

Fig. 3 is a detail of the top of the lamp showing a modified form of construction.

50 The body 10 of the lamp may take any desired form, and is here shown, of the type ordinarily used on semaphores. This body is closed at the bottom, its upper portion 11 is shown as contracted in diameter to constitute what is known as the dome. This

dome is provided with a plurality of air induction ports 12, 13, represented as arranged in two annular series. A central conical flue 14 is located on the axis of the body, projecting into the dome above the ports 12. 60 An annular plate 15, preferably imperforate, extends from the flue to the side walls of the dome, and a foraminous screen 16 extends from the wall of the dome to the wall of the flue and is here shown as cylindrical in form. 65

The upper portion of the dome 17 is in the form of a truncated cone and open at the top to form an outlet for the vapors of combustion. A concave cap 18 is mounted above the dome 17 for the purpose of excluding 70 rain and snow from the flue. As thus far described, the lamp is of known construction.

An annular cap 19 fits around the conical portion 17 of the dome and covers the ports 75 12, 13. The depending portion of the cap 19 is of greater diameter than the dome and is open at the bottom, thereby forming with the dome wall a chamber 20 through which air gains access to the induction ports. The 80 bottom rim of the cap 19 is flanged outwardly, as shown at 21, this flange being substantially horizontal.

In the modification shown in Fig. 3, in lieu of the cap 19 there is shown an annular 85 plate 22 fitting upon the conical portion 17 of the dome and extending out horizontally above the induction ports 12, 13.

The cross-sectional configuration of the dome of the lamp is immaterial, and may 90 follow common practice, the dome being sometimes circular and sometimes polygonal. In either case the cap 19 or 22 should correspond in shape to the dome.

The outstanding flange 21 or flat cap 22 95 prevents the disturbance or reversal of the draft by downrushing air currents, the construction shown in Fig. 1 being the more efficient and especially desirable because it guards the air ports against the entrance of 100 rain or snow.

The precise movements of the air currents cannot be well determined except theoretically. It is my supposition that without a guard flange such as 21 or 22 the descending 105 currents of air, in sweeping across the induction ports, produce a suction action and cause the troubles now sought to be cured. By projecting a guard flange, such as 21 or 22, across the path of the disturbing air cur- 110

rents they will break over its edge and enter the ports instead of inducing an outward flow therethrough.

I do not positively assert the precise nature of the action which takes place, but from actual tests I am able to say definitely that when the induction ports are guarded by an outstanding plate, flange or ledge projecting substantially perpendicular to the direction of movement of the descending currents, the disturbance of circulation of the lamp is not interfered with. I therefore use the term "substantially horizontal" as defining the positioning of the plate in this broad sense.

Nor do I wish to be limited to the particular construction or constructions disclosed in the drawings, as any element for guarding the induction ports having an edge across which the descending currents must cut, will come within the scope of the invention.

I claim as my invention—

1. In a top draft lamp, in combination, a body having a dome provided with lateral air induction ports and a central discharge flue, and a shield plate projecting substantially horizontally from the dome.

2. In a top draft lamp, in combination, a body having lateral induction ports at its upper end and a central discharge flue, and a shield plate projecting substantially horizontally and guarding the induction ports against vertically moving air currents.

3. In a top draft lamp, in combination, a body having lateral induction ports at its upper end, and a cap inclosing the upper end of the body and depending below the ports and being open at its lower end and having at such end an outstanding substantially horizontal flange.

4. In a top draft lamp, in combination, a body having its upper end contracted to form a dome and having lateral induction ports in the dome portion and a central flue, a cap inclosing the dome and depending in front of the ports and being open at its bottom and having an outstanding substantially horizontal flange.

5. In a top draft lamp, in combination, a body having a dome provided with lateral air induction ports and a central discharge flue, and a shield attached to the dome above the ports and comprising a substantially horizontal outstanding plate.

WILLIAM S. HAMM.
